UNITED STATES PATENT OFFICE.

ERNEST L. B. ZIMMER, OF OAKLAND, CALIFORNIA.

SELF-CLEANING BAG FOR VACUUM-CLEANERS.

1,124,574.

Specification of Letters Patent.

Patented Jan. 12, 1915.

Application filed March 23, 1914. Serial No. 826,635.

To all whom it may concern:

Be it known that I, ERNEST L. B. ZIMMER, a citizen of the United States, residing at Oakland, in the county of Alameda and 5 State of California, have invented new and useful Improvements in Self-Cleaning Bags for Vacuum-Cleaners, of which the following is a specification.

This invention relates to improvements in 10 dust bags for vacuum cleaners and the like; and the objects are first, to provide a simple, durable, easily operated bag which is so constructed that it may be used in connection with any type of vacuum apparatus using 15 bags; and second, to provide automatically actuated means for vibrating the walls of the bag to prevent the dust from settling and caking on same.

The invention further consists of the parts 20 and the construction and combination of parts as hereinafter more fully described and claimed, having reference to the accompanying drawing in which—

Figure 1 is a perspective view, showing the 25 frame for the dust bag. Fig. 2 shows the application of the invention.

Referring to the drawing, A indicates in 30 general a frame which consists of a centrally disposed tube 2, a head 3, and a conical shaped spider frame 4. The lower surface of head 3 is provided with a downwardly turned flange 5, between which and the outer edge of the spider frame 4 a series 35 of coil springs 6 are interposed. The spider frame, together with the head 3, may be secured to the central tube 2 by being screwed into same, or in any other suitable manner, and similarly secured to the extreme lower 40 end of the tube 2, is a funnel shaped member 7, the lower open end of which is covered with fine wire cloth, or like material, indicated at 8.

The lower surface of the spider frame is 45 covered with a coarse screen, indicated at 9, and this frame, together with head 3, and connecting tube 2, serves the purpose of a frame, on the outside of which a suitable form of canvas bag 9' is secured. The coarse screen 9, together with the several 50 coil springs, indicated at 6, are provided for the purpose of holding the bottom and sides of the bag in the extended position shown in Fig. 2. The operation and application of the device constructed as here shown will be 55 as follows:

B indicates a suitable form of tank, or

cylinder, into which the bag-supporting frame A may be inserted. The outer flange of head 3 may be bolted to the upper end of tank B, as indicated at 10, or may be otherwise secured.

11 indicates a pipe which may be connected with a vacuum pump, not here shown. This pipe communicates with the central tube 2 within the bag frame. 12 indicates 65 a pipe to which the suction hose is attached, and 13 a suitable form of opening through which the dust may be removed from the tank. The moment suction is applied to pipe 11, it will immediately be transmitted 70 through central tube 2, and the screened opening 8 secured on the lower end thereof. A vacuum will thus be produced with the bag, and this is in turn transmitted to the interior of the tank B and pipe 12. The 75

dirt entering through the suction hose and pipe 12, when the apparatus is being used, will thus enter the cylinder or tank B, and will consequently have a tendency to collect on the outer surface of bag 9. Any accumulation of dirt on the exterior of the bag is, however, prevented by the automatic action of spring coil 6. The slight pulsations transmitted through pipe 11 from the pump will have a tendency to continuously vibrate 85 the coil springs 6, and this will in turn transmit the vibration to the surface of the dust bag, and prevent any settling or caking of dust on the exterior surface of same. It sometimes happens that the canvas bags will 90 crack or rip, for some reason or other, and the dust would then enter directly through pipe 11 into the pump, with consequent ruinous action. This danger is, however, eliminated in this instance, by providing the funnel shaped member 7, the lower surface of 95 which is covered with a wire cloth 8. The dust which would otherwise pass directly through tube 2 and pipe 11 to the pump, is in this instance, caught on the lower surface 100 of the wire cloth 8, and the accumulation on said surface, as this is very small, will soon become sufficiently great to practically choke the pump. The operator will then immediately know that something is wrong, 105 and consequently, shut down for repairs.

A dust bag, constructed and operated in the manner here shown is simple, durable and highly efficient in action. It not only produces a large filtering surface, with subsequent reduction of pull on the pump, but 110 is also automatic and self-cleaning in action.

The bag, with connected frame, can be used in connection with paint and cement mills, or with various forms of vacuum cleaner systems now in use.

5 I wish it understood that various changes in form, proportions and minor details of construction may be resorted to within the scope of the appended claims and that I do not wish to limit myself to the specific design and construction here shown.

10 Having thus described my invention, what I claim and desire to secure by Letters Patent is:

15 1. An apparatus of the character described, comprising a bag frame consisting of a head and bottom section, a plurality of coil springs connected at their upper ends to the outer edge of the head section and at the lower ends to the outer edge of the 20 bottom section, a dust bag covering the frame, the inner surface or sides of the bag being supported and held in an extended position by the coil springs, and a central tube passing through the head section and 25 adapted to support the head and bottom sections in fixed spaced relation, said tube also adapted to act as a conduit for air passing through the bag.

30 2. In an apparatus of the class described, a bag frame comprising an upper and a lower head, a centrally positioned tube connecting said heads, a plurality of coil springs interposed between the upper and lower head, and a dust bag covering the 35 frame, the inner surface of said bag being so positioned as to contact with said coil springs.

3. In an apparatus of the class described, 40 a dust bag, a bag frame within the bag, said frame comprising a head to which the bag

is secured, a downwardly extending tube secured to said head, a strainer secured on the lower end of said tube, a spider frame secured to the lower end of the tube, and a plurality of coil springs secured at their 45 upper ends to the head and at their lower ends to the spider frame.

4. An apparatus of the character described, comprising a bag frame consisting of a connected head and bottom section having a plurality of coil springs connected at their upper ends to the outer edge of the head section and at the lower ends to the outer edge of the bottom section, a dust bag covering the frame, the inner surface or 55 sides of the bag being supported and held in an extended position by the coil springs, a tank in which the bag and frame are mounted, and a connection formed on the head of the bag frame by which communication is made between the interior of the bag and a suction pump.

5. An apparatus of the character described, comprising a bag frame consisting of an upper and lower head, a standard on 65 the ends of which the heads are secured and held in spaced relation, a plurality of coil springs connected at their upper ends to the outer edge of the upper head and at their lower ends to the outer edge of the lower head, and a dust bag covering the frame, the surface or sides of the bag being supported by the coil springs.

In testimony whereof I have hereunto set my hand in the presence of two subscribing 70 witnesses.

ERNEST L. B. ZIMMER.
